UNITED STATES PATENT OFFICE.

OLIVER M. EDWARDS AND HOWARD ALBERT CRONMILLER, OF SYRACUSE, NEW YORK,
ASSIGNORS TO THE O. M. EDWARDS COMPANY, INC., OF SYRACUSE, NEW YORK, A
CORPORATION OF NEW YORK.

WINDOW-SASH CONSTRUCTION.

Application filed October 16, 1924. Serial No. 743,965.

This invention relates to window sashes, such as are used in railway cars and motor busses and the like, and particularly in motor busses where the sash must be extremely light and at the same time strong and has for its object a sheet metal window sash which is particularly light and strong and rigid in construction and highly efficient and durable in use.

10 The invention consists in the novel features and in the combinations and constructions hereinafter set forth and claimed.

In describing this invention, reference is had to the accompanying drawings in which 15 like characters designate corresponding parts in all of the views.

Figure 1 is a front elevation of a sash embodying our invention.

Figure 2 is a sectional perspective view 20 on line 2—2, Figure 1.

Figure 3 is a view similar to Figure 2 of another embodiment of our invention.

In sheet metal window sashes for motor busses, owing to the lightness of the material, the sash members and especially the lower rail is liable to weave or distort during raising and lowering of the window, and this invention has for its object means for reenforcing the sash member and particularly the lower rail without adding prohibitive weight or bulk thereto and also providing a way or guide for a rubber buffer or weather strip, such reenforcing means also stiffening the sash rail against spreading, due to the 35 action of the weather or buffer strip when engaging or resting on the sill.

This sash comprises generally, a sheet metal window sash having rails and stiles in the form of a channel open at their edges, 40 these members being joined and stiffened by corner irons located within said members and means for re-enforcing the lower rail of the sash on which the handles are mounted and which rail is subject to twisting and weaving strains during the raising and lowering of the window sash.

1 designates the stiles and 2 and 3 the upper and lower rails.

4 designates the corner irons which are 45 angular in form and to which the stiles and rails are connected as by clamping members or screws 5, these corner irons being located in the channels of the stiles and rails.

The reenforcing means is a strip in the

form of a channel 6 having its side flanges 55 7 lying against the front and rear walls of the sash member and preferably extending between the inner margins of said side walls of the sash member and the walls 8 of an external groove 9 formed in the bottom of 60 the channel formation of the sash member, the bottom of the reenforcing strip being preferably located toward or opposed to the open edge of the sash member or rail 3. The groove 9 is for the purpose of receiving the margin of the glass pane in the usual manner.

The reenforcing strip 6 is located between the corner irons of the lower rail 3, but not joined thereto and may be continuous or as 70 shown in Figure 1, it may be made up of two or more sections spaced apart. The side flanges are secured to the opposing walls of the sash member by sweating, soldering, etc. The front and rear walls of the 75 sash member are provided with inturned flanges 10 at the open edge of the sash member and the bottom 11 of the reenforcing strip is opposed to these flanges 10 and forms a passage or guide for a weather or buffer 80 strip 12 having a base portion 13 located between the bottom 11 of the reenforcing strip and said flanges 10. These flanges 10 extend into grooves in the sides of the weather strip 12.

85 The handles, not shown, for the sash, are located on the front wall of the sash member or lower rail 3 and the force applied to lift the sash tends to twist said member 3, especially if there is a handle at the 90 center of the lower rail, or when two handles are used and so located relatively to the joints at the corners of the sash that some of the lifting force applied to the handles tends to twist the lower rail. Also 95 oftentimes a person in raising the window takes hold of the lower rail at or near the center and lifts the sash, after preliminarily releasing the latches and partly opening the window. In so lifting the sash he applies a weaving, twisting or bending force 100 to the lower rail. The reenforcing strip 6 gives sufficient rigidity to the rail 3 to prevent undue twisting and weaving thereof, and also when the window closes, the strain 105 on the buffer or weather strip 12, when it comes into engagement with the sill, tends to bend or spread the front and rear walls

of the rail 3 outwardly. The reenforcing strip prevents such bending outwardly or spreading of the sash member. Also the bottom of the strip forms an abutment for 5 the base portion 13 of the weather strip. The bottom of the reenforcing strip also prevents bending and binding of the flanges 10 on the weather strip when the weather strip is being slid into the sash member, so 10 that the reenforcing strip facilitates the attachment of the weather strip to the sash.

In Figure 3, the side flanges 14 of the reenforcing strip are shown as of less height than the side flanges 7 of the weather strip 15 6, shown in Figure 2. However, in each case, the reenforcing strip prevents twisting and weaving of the light sheet metal sash when the buffer or weather strip is engaged with the sill and supporting the 20 weight of the sash.

What we claim is:

1. In a metal window sash construction, the combination of a sash member in the form of a channel having front and rear 25 walls, the channel being open at the edge of the sash and the front and rear walls being formed with inturned flanges at the edge of the channel, the edges of the flanges being spaced apart leaving a slot which constitutes the entrance of the channel of the hollow sash member, a reinforcing member interposed between the walls of the channel and secured thereto, the reinforcing member being spaced apart from the flanges forming 30 35 a way, the reinforcing strip holding the flanged margins of the sides of the sash member from flexing and spreading, a weather strip having a base arranged in the way and formed with grooves for receiving

the flanges, the reinforcing strip extending 40 the greater part of the length of the sash member between the corners of the sash.

2. In a metal window sash construction, the combination of a sash, a thin sheet metal member in the form of a channel having front and rear walls, the channel being open at the edge of the sash and the front and rear walls being formed with inturned flanges at the edge of the channel, the edges of the flange being spaced apart leaving a 50 slot which constitutes the entrance of the channel of the hollow sash member, a reinforcing member interposed between the walls of the channel and secured thereto, the reinforcing strip being spaced apart from the flanges forming a way, the reinforcing strip holding the flanged margins of the sides of the way from flexing and spreading, a weather strip having a base arranged 55 60 in the way and formed with grooves for receiving the flanges, the reinforcing strip extending the greater part of the length of the sash member between the corners of the sash, and being spaced apart from the base of the weather strip and from said inturned flanges, the reinforcing strip having flanges lapping the walls of said channel and extending away from said inturned flanges whereby the margins of the walls formed 65 70 with the inturned flanges below the reinforcing strip form the sides of the way for the base of the weather strip.

In testimony whereof, we have hereunto signed our names at Syracuse, in the county of Onondaga, and State of New York, this 75 25th day of September, 1924.

OLIVER M. EDWARDS.

HOWARD ALBERT CRONMILLER.
